UNITED STATES PATENT OFFICE.

GEORGE W. CHRISTOPH AND HENRY F. HART, OF HARTFORD, CONNECTICUT.

SHEET-MATCH.

SPECIFICATION forming part of Letters Patent No. 673,420, dated May 7, 1901.

Application filed February 26, 1900. Serial No. 6,471. (No model.)

To all whom it may concern:

Be it known that we, GEORGE W. CHRISTOPH and HENRY F. HART, citizens of the United States, residing at Hartford, in the 5 county of Hartford and State of Connecticut, have invented certain new and useful Improvements in Friction-Matches, of which the following is a specification.

This invention relates to a combustible 10 sheet which is provided with a compound that may be ignited by being brought into frictional contact with a compound having the proper affinity.

The object of this invention is the production 15 of a continuous sheet of this nature that is adapted to be rolled and placed in a machine designed to feed the sheet and cut an individual match.

The invention consists of a sheet of flexible 20 combustible material that is capable of being rolled, as paper, pulp, cloth, or similar material having the desired characteristics, with one edge of the sheet coated with a frictional igniting compound.

25 Referring to the accompanying drawings, Figure 1 shows a perspective view of a roll embodying the invention. Fig. 2 shows a sectional view of a machine in which such a roll may be placed for feeding and cutting the 30 individual matches, and Fig. 3 shows one of the separated matches.

The sheet 1 can be made of any combustible 35 material that is thin enough to be rolled for placing in and to be sheared by the cutters of the machine for which it is intended. For this purpose the sheet may be formed of paper or pulp having the necessary characteristics, or it may be formed of cloth or other fabric, substance, or compound properly 40 treated. This sheet may be rolled into a bundle or package, as shown in Fig. 1, or it may be folded, if desired. A quantity of igniting compound 2 in a fluid or plastic condition is deposited upon both surfaces along one edge 45 the entire length of the sheet. The formula of the igniting compound may be any of those commonly used for friction-matches; but it

is desirable that it be such as will produce a compound that will only ignite when rubbed upon or brought into contact with a compound for which it has a proper affinity. The igniting compound is preferably applied and allowed to harden before the sheet is rolled. The edge of the sheet opposite that which is provided with the igniting compound may be 50 treated with a fireproofing compound 3 of a nature similar to that on matches in common use. These rolled sheets are designed to be placed in the receiving-chamber of a machine, which is provided with feed-rollers for 55 intermittently feeding the sheet from the machine and with shear-blades for shearing off the fed portions—such, for instance, as is shown and described in the application for 60 patent, Serial No. 6,472, filed by us on February 26, 1900, and to which reference is made for a full detailed description. This machine is illustrated in Fig. 2 of the accompanying 65 drawings and operates as follows: Upon the depression of the hand-lever 4 the blade 5, which is secured to the lower edge of the hand-lever, severs a transverse strip from the sheet, which strip is shown in Fig. 3. When this lever 4 is lifted, a sufficient portion of the sheet is fed from the receiving-chamber 6 by the feed-rollers 7 to furnish another match, when the lever operating the 70 blade is again depressed. The upper feed-roller is given an intermittent rotary motion by the engagement of the pawl 8 as it is moved backward with the teeth of the ratchet-wheel that is connected with the feed-roller. The pawl 8 is attached to the plunger 9, which is thrown forward by its spring when the lever is lifted and is forced backward by the 75 engagement of the edge of the lever with the end of the plunger when the lever is depressed. The lower feed-roll simply rotates by friction. 80

Sheets of match material made in this manner are very cheap to manufacture, and they 85 provide an article which is particularly designed for machines such as mentioned in said pending application, which are adapted to be placed in public localities—such as ci-

gar-stores, hotel lobbies, restaurants, bar-
rooms, hotel apartments, and public offices—
for furnishing matches to patrons.

We claim as our invention—

- 5 As a new article of manufacture a sheet of
flexible, combustible material, that is capa-
ble of being rolled and of being sheared, and
that has a coating of igniting compound along
one edge the entire length of the sheet and a

coating of fireproofing compound along the ¹⁰
other edge the entire length of the sheet, sub-
stantially as specified.

GEORGE W. CHRISTOPH.
